UNITED STATES PATENT OFFICE.

CHARLES E. McMANUS, OF NEW YORK, N. Y.

BOTTLE-CLOSURE.

1,339,066.

Specification of Letters Patent. Patented May 4, 1920.

Application filed November 17, 1915. Serial No. 61,909.

To all whom it may concern:

Be it known that I, CHARLES E. McMANUS, a citizen of the United States, residing at the borough of Manhattan, in the city, 5 county, and State of New York, have invented certain new and useful Improvements in Bottle-Closures, of which the following is a specification, reference being had therein to the accompanying drawings, 10 which form a part thereof.

My invention relates to bottle closures and more particularly to a type of metal caps containing therein a compressible disk adapted to engage and seat upon the lip 15 of a bottle to seal the bottle.

In closures of this character the compressible disk is ordinarily formed of sheet cork or of a composition composed of granular cork, the particles of which are united by 20 an insoluble, gas and acid proof, binder.

The type of closure referred to above, while extensively used by bottlers, has certain objectionable characteristics, the correction of which is the object of my invention. 25

In producing closures of this character for commercial use, it is practically impossible to secure disks, whether of cork or of a composition; all of which will have a perfectly smooth, continuous surface and have 30 the same degree of compressibility.

The inequality of different disks is not apparent from inspection and can be determined only after the cap has been placed 35 upon a bottle. If there be surface flaws upon the disk and if the compressibility of the disk be insufficient to permit the complete closing of these flaws, the gases within the bottle will, after the cap is placed upon 40 a bottle, find a passage to atmosphere by reason of the defective sealing of the neck of the bottle, and thus cause the contents of the bottle to "go flat." Bottles thus imperfectly sealed are known in the bottling 45 trade as "leakers" and the percentage of such "leakers" is sufficiently high to cause this defect to be a source of considerable loss. When bottling beer "leakers" will ordinarily develop during the sterilization 50 of the bottled beer but it is not uncommon to have "leakers" develop even when the seal seems to be perfectly tight after a test by the bottlers.

In addition to the development of "leak-

ers" by reason of defects in the disk, contact 55 of the contents of the bottle with the cork or other material of a disk will have the effect of imparting an undesirable flavor or taint to said contents, a condition which is particularly true of some composition disks. 60 Furthermore, there is a likelihood of small particles of cork being separated from the disk and falling within the bottle, which is more likely to occur with composition disks than with solid cork disks, although 65 the latter are not free from this objectionable condition.

By my invention I provide a bottle closure having all of the desirable characteristics, so far as securing a tight joint is concerned, 70 present in the ordinary closure having a cork or composition disk, and in addition thereto having the characteristics of protecting the contents of the bottle from contamination by contact with the disk and preventing the 75 escape of particles of cork from the disk, into the bottle. Furthermore, the surface of the cushion of the disk exposed within the neck of the bottle is so formed as to present a smooth continuous surface and 80 thus minimize likelihood of "leakers" while preserving all of the compressibility or elasticity inherent to the cork or composition disk.

The invention consists primarily in a bottle closure embodying therein a metallic cap, a compressible disk within said cap, and a flexible disk of non-absorbent material superimposed upon, and united by means of a binding agent with, said compressible disk, 85 said superimposed disk being of smaller diameter than said compressible disk whereby a sufficient portion of the surface of said compressible disk is exposed to permit the sealing of the bottle directly against said 90 compressible disk and the portion of the compressible disk within the neck of the bottle is protected by said flexible disk; and in such other novel features of construction and combination of parts as are herein- 95 after set forth and described and more particularly pointed out in the claims here- 100 to appended.

Referring to the drawings:

Figure 1 is a sectional view of a portion 105 of the neck of a bottle showing my improved closure thereon, said closure being shown in section;

Fig. 2 is a bottom view of the closure;

Fig. 3 is a perspective view of the flexible disk; and

Fig. 4 is a perspective view of the compressible disk.

Like letters refer to like parts throughout the several views.

In the accompanying drawings, the neck 10 of the bottle is indicated at *a*, the configuration of the lip *b* of the bottle and the portion of the neck adjacent thereto being that ordinarily employed with bottle closures of the type to which this invention relates.

In the form of closure shown in the accompanying drawings, there is presented an embodiment of my invention which I preferably employ although it is not my intention to limit the invention to this particular form.

20. In this embodiment of the invention, I have shown at *c* an ordinary metallic cap having a convoluted rim *d* adapted to pass over and be clamped under the lip of the bottle. Seated within and united to the cap 25 *c* is a disk *e* of compressible material. This disk extends to a point adjacent the flange *d*. The manner of securing said disk in its position relatively to the cap, may be that ordinarily employed in closures of this type, 30 the union of the disk to the cap ordinarily including the use of a fusible binding medium interposed between the cap and the disk, and set in a manner to unite the parts by the application of heat and pressure simultaneously or successively.

The disk *e*, as shown in the accompanying drawings is what is known in the art as a "composition disk", being composed of granular cork formed into a sheet of the 40 desired thickness by means of a binder having the same qualities of insolubility as the medium used in securing the disk in the cap.

A composition disk combined with a 45 metallic cap, as heretofore described, is old and well-known in this art and I make no claim of invention thereto. The medium used as a binder for the granular cork, and in attaching the disk to the cap, are also old 50 and well-known to those skilled in the art, and this old and well-known medium, or any other desired medium, fusible only at a temperature above that at which bottled beverages are sterilized, may be used.

55. My invention relates more particularly to a construction of closure wherein that portion thereof exposed to the liquids within the bottle is so protected as to prevent contamination of the liquid by contact with the 60 disk, and the dropping of small particles of cork or other material of which the disk is composed, into the liquid. This construction also assists in securing a gas tight joint by the closure of any surface flaws or defects in the disk.

My invention contemplates the utilization in conjunction with the metallic cap *c* and compressible disk *e*, of a flexible disk *f*, superimposed upon the disk *e* and completely covering that surface area of the 70 disk *e* which is exposed within the neck of a bottle when the closure is applied thereto.

This disk *f* may be made of a hard parchment paper, or of any other paper so treated as to make it non-absorbent. This flexible 75 disk *f* is secured in place upon the compressible disk *e* by means of a binding medium, preferably such as that which is used as a bond for the granules of the composition disk or for uniting said disk to the 80 metallic cap. By using this bond, the disk *e* and the disk *f* may be assembled in relation to the cap and to each other by one and the same operation if desired.

The purpose of the disk *f* is not to assist 85 in forming the seal between the closures and the bottle lip but to prevent the presence of channels through which gas may escape and to prevent contact of the liquid with the compressible disk. To secure the 90 desired action of the superimposed flexible disk *f*, I make it of a smaller diameter than the disk *e* and position the center of the disk *f* directly over the center of the disk *e*, thus exposing a sufficient portion of the 95 surface of the disk *e* to permit the sealing of the neck of the bottle directly against the material of said disk. The width of this exposed portion is such as to bring the edge of the disk *f* up to the line of contact 100 of the disk *e* with the lip of the bottle, thus insuring protection of the entire surface of the disk *e* within the neck of the bottle. Exactitude in the positioning of the disk *f* with relation to the disk *e* is of great importance as the projection of any portion of the disk within the area of the contact surface of the disk *e* would result in "leakers" 105 and thus make the closure worthless. Accuracy in the positioning of the disk *f*, in 110 the commercial production of caps of the character herein described, may be secured mechanically in a number of different ways and by means of a variety of different mechanisms and the manner of assembling 115 the device, or the mechanism employed in so assembling it, is immaterial to the invention of this application.

It will be apparent that superimposing the disk *f* in the manner described upon the disk *e*, will have the effect of sealing all surface imperfections in the disk *e* about the center thereof and to a point co-incident with the point of engagement of said disk with the neck of the bottle. When the closure is in position upon a bottle, the disk *f* being non-absorbent, impervious to gas, insoluble and acid proof, will prevent contact of the liquid in the bottle with the material of the disk *e*. The thinness and flexibility 130

of the disk *f* will permit it to readily adapt itself to any changes of form in the disk *e* resulting from the compression thereof at the edge without likelihood of the 5 formation of channels through which the gases within the bottle may escape.

My invention is particularly adapted to closures employing compressible disks embodying therein granular cork, as in this 10 form of closure, there is greater likelihood of slight contamination of the liquid contents of a bottle and there is also greater likelihood of the separation of small granules of cork from the main body and the 15 presence of such small granules in the liquid in the bottle. Furthermore, with a composition disk, the binding medium employed for attaching the disk *f* to the disk *e* will readily combine with the binding material 20 for the disk itself and thus form a close intimate bond between the two disks.

The use of the disk *f* will also tend to prolong the effective life of the disk *e* by preventing the gases and liquid in a bottle 25 contacting with any filling or surfacing medium which may be used upon the disk *e*.

I have referred herein to the fact that the disk *f* does not extend into the area of the contact surface of the disk *e*. By this I do 30 not mean that the disk *f* must not contact with the neck of the bottle, but that it must be within that portion of the disk *e* which is subjected to the compression necessary to secure a tight sealing of the bottle. In applying a closure of this type to a bottle, a 35 channel is formed in the disk *e* by the top of the bottle lip, the line of greatest compression being centrally of said channel. The disk *f* is so positioned as to be spaced 40 within said line of greatest compression and yet it may be, and preferably is, in contact with the inner edge of the bottle lip; and thus forms a double seal, one between the disk *e* and the top of the lip of the bottle, 45 and the other between the disk *f* and the inner edge of said lip.

It is not my intention to limit the invention to the precise details of construction shown in the accompanying drawings, it 50 being apparent that such may be varied without departing from the spirit and scope of the invention.

Having described the invention, what I claim as new and desire to have protected by 55 Letters Patent is:—

1. A bottle closure embodying therein a metallic cap, a compressible disk within said cap, and a flexible disk of non-absorbent material superimposed upon, and united 60 by means of a binding medium with, said compressible disk, said superimposed disk being of smaller diameter than said compressible disk, whereby a sufficient portion of the surface of said compressible disk is exposed to permit the sealing of the bottle 65

directly against said compressible disk and the portion of the compressible disk within the neck of the bottle is protected by said flexible disk.

2. A bottle closure embodying therein a 70 metallic cap, a compressible disk within said cap, and a thin non-absorbent, non-porous paper disk superimposed upon, and united by means of a binding medium to, said compressible disk, said paper disk being of 75 smaller diameter than said compressible disk, whereby a sufficient portion of the surface of said compressible disk is exposed to permit the sealing of the bottle directly against said compressible disk, and the portion of 80 the compressible disk within the neck of the bottle is protected by said flexible disk.

3. A bottle closure embodying therein a metallic cap, a compressible disk within said cap, and a flexible disk of non-absorbent 85 material superimposed upon, and united by means of a fusible binding medium with, said compressible disk, said superimposed disk being of smaller diameter than said compressible disk, whereby a sufficient portion 90 of the surface of said compressible disk is exposed, to permit the sealing of the bottle directly against said compressible disk and the portion of the compressible disk within 95 the neck of the bottle is protected by said flexible disk.

4. A bottle closure embodying therein a metallic cap, a compressible disk composed of granular cork and a binding medium within said cap, and a flexible disk of non-absorbent material superimposed upon, and united by means of a binding medium with, 100 said compressible disk, said superimposed disk being of smaller diameter than said compressible disk, whereby a sufficient portion 105 of the surface of said compressible disk is exposed, to permit the sealing of the bottle directly against said compressible disk and the portion of the compressible disk within 110 the neck of the bottle is protected by said flexible disk.

5. A bottle closure embodying therein a metallic cap, a compressible disk composed of granular cork and a fusible binding medium within said cap, and a flexible disk of 115 non-absorbent material superimposed upon, and united by means of a fusible binding medium with, said compressible disk, said superimposed disk being of smaller diameter than said compressible disk, whereby 120 a sufficient portion of the surface of said compressible disk is exposed, to permit the sealing of the bottle directly against said compressible disk and the portion of the compressible disk within the neck of the 125 bottle is protected by said flexible disk.

6. A bottle closure embodying therein a metallic cap, a compressible disk within said cap, and a flexible disk of non-absorbent material superimposed upon, and united 130

by means of a binding medium with, said compressible disk, said superimposed disk being of smaller diameter than, and having its center coincident with the center of, said compressible disk, whereby a sufficient portion of the surface of said compressible disk is exposed, to permit the sealing of the bottle directly against said compressible disk and the portion of the compressible disk within the neck of the bottle is protected by said flexible disk.

7. A bottle closure embodying therein a metallic cap, a compressible disk composed of granular cork, and a fusible binding medium within said cap, and a thin non-absorbent, non-porous paper disk superimposed upon, and united by means of a fusible binding medium to, said compressible disk, said paper disk being of smaller diameter than said compressible disk, whereby a sufficient portion of the surface of said compressible disk is exposed to permit the sealing of the bottle directly against said compressible disk, and the portion of the compressible disk within the neck of the bottle is protected by said flexible disk.

8. A bottle closure embodying therein a metallic cap, a compressible disk secured within said cap by means of a fusible binding medium, and a flexible disk of non-absorbent material superimposed upon, and united by means of a fusible binding medium with,

said compressible disk, said superimposed disk being of smaller diameter than said compressible disk, whereby a sufficient portion of the surface of said compressible disk is exposed, to permit the sealing of the bottle directly against said compressible disk and the portion of the compressible disk within the neck of the bottle is protected by said flexible disk.

9. A bottle closure embodying therein a metallic cap, a compressible disk composed of granular cork, and a fusible binding medium secured within said cap by means of a fusible binding medium, and a thin non-absorbent, non-porous paper disk superimposed upon, and united by means of a fusible binding medium to, said compressible disk, said paper disk being of smaller diameter than said compressible disk, whereby a sufficient portion of the surface of said compressible disk is exposed to permit the sealing of the bottle directly against said compressible disk, and the portion of the compressible disk within the neck of the bottle is protected by said flexible disk.

In witness whereof I hereunto affix my signature in the presence of two subscribing witnesses, this 15th day of November, 1915.

CHARLES E. McMANUS.
